ATTYS

UNITED STATES PATENT OFFICE.

CHARLES A. BRAINERD, OF CHICAGO, ILLINOIS.

PICTURE-FRAME.

SPECIFICATION forming part of Letters Patent No. 236,667, dated January 18, 1881.

Application filed March 18, 1880. (Model.)

To all whom it may concern:

Be it known that I, CHARLES A. BRAINERD, of Chicago, in the county of Cook and State of Illinois, have invented a new Improvement 5 in Picture-Frames; and I do hereby declare the following to be a full, clear, and exact description of the same, reference being had to the accompanying drawings, and to the letters of reference marked thereon.

10 This invention is a blank of special construction, which is adapted to form, when properly folded and pasted, a picture-frame or photograph-stand, as will be fully described hereinafter.

15 In the drawings, Figure 1 represents a plan view of the blank, and Fig. 2 represents a side elevation of the stand or frame complete.

To enable others skilled in the art to make and use my invention, I will now proceed to 20 describe fully its construction and manner of operation.

In Fig. 1, A represents the blank, of any proper material, paper being preferred, which is formed by means of proper stamps or cutter 25 from a single sheet.

a represents the main portion of the blank, of quadrangular form, which forms the front piece of the stand or frame when the same is completed, which main portion is provided 30 with a sight-opening, X, as shown. a' a' represent projections which serve as legs for supporting the same.

b represents an auxiliary portion, attached to the part a, which, when folded upon the line 35 x, forms the back frame of the stand.

b' b', Fig. 2, represent ears upon the part b, by means of which the latter is secured to the part a, as shown, by pasting or otherwise.

c represents a tongue cut in the part b, which, when the stand is completed, is adapted 40 to serve as a brace-bar or support for holding the same in its proper position, as shown.

After the blank has been properly cut, the stand may be readily completed by simply bending the part b upon the line x, and then 45 pasting the ears b' to the part a. A very desirable stand can thus be produced at a very small cost.

The face of the stand or frame may be painted with any proper design, or be otherwise 50 embellished, according to taste.

Having thus fully described my invention, what I claim as new, and desire to secure by Letters Patent, is—

1. The blank A, having the main portion a 55 of quadrangular form, with central sight-opening, X, the auxiliary portion b, and tongue c, formed in one piece, as described.

2. As a new article of manufacture, a picture-frame having the main portion a, with 60 sight-opening X, as shown, the auxiliary portion b, and tongue c, formed of one piece, and constructed and adapted for use as described.

This specification signed and witnessed this 8th day of March, 1880.

C. A. BRAINERD.
